PRIMING SYSTEM FOR INTERNAL
COMBUSTION ENGINES

Roscoe Alexander Coffman, Pittsburgh, Pa.

Application July 19, 1934, Serial No. 736,097

12 Claims. (Cl. 123—187.5)

This invention relates broadly to priming systems for internal combustion engines and more particularly to priming systems adapted for use with airplane engine starters of the type illustrated in my Patents Nos. 1,776,228 and 1,946,309.

Heretofore, it has been found exceedingly difficult to start airplane engines and this has been particularly true when attempts have been made to start such engines at low temperatures. This difficulty is partly due to the fact that airplane engines are not equipped with devices commonly known as chokes, such as those found on automobiles. By reason of the fact that airplane engines have not been equipped with chokes it has become necessary to install priming systems on such engines which systems are most commonly operable from the cockpit by means of a small hand pump for forcing liquid gasoline into the manifolds of the engine or in some cases directly into the engine cylinders.

With the present priming systems fuel in its liquid state is admitted to the manifolds or cylinders of the engine in the form of a small stream, and at low temperatures the fuel so admitted does not vaporize and mix with the ingoing air to create an explosive mixture. In some cases this is due to the fact that the fuel is admitted at an improper point and in other cases, it is due to the fact that too much priming is done prior to the attempt to start. It is a well known fact that wet fuel will not burn readily and it is furthermore well known that wet fuel drawn into the cylinders of an engine will foul the spark plugs and will also wash the lubricating oil off the walls of the pistons and cylinders. The unfavorable results attendant upon such conditions are well known.

Prior to the development of my engine starters mentioned above and also shown in my Patent No. 2,005,913 there were no starting devices of sufficient capacity to rotate an engine crankshaft satisfactorily at a temperature below zero without first warming up the engine. At higher temperatures it has been possible to vaporize sufficient fuel with priming devices heretofore developed to start an engine and due to this no attempts have been made to develop priming systems which will operate efficiently at lower temperatures.

It has been found that my engine starter is sufficiently powerful to rotate an airplane engine crankshaft at sub-zero temperatures as low as -30° F. and at a rate of speed of 250 R. P. M. and this has brought to light the need of more adequate priming under these conditions.

It is toward this end, therefore, that I have made the present invention and it is an object of my invention to provide a priming system which will operate in timed relation with a power starter.

It is a further object of my invention to provide a priming system in which the fuel is broken into minute particles and injected into the manifold or cylinders of the engine in timed relation with the rotation of the engine crankshaft and under pressure generally in excess of 100 pounds per square inch.

It is a further object of my invention to provide a priming system which will introduce fuel to the manifold or cylinders of an internal combustion engine in a fine state of subdivision without the aid of the usual carbureting devices.

It is a further object of my invention to provide a priming system which will operate and be timed automatically in relation to the engine 20 starter and which thereafter may be manually assisted in its continued operation, and a system wherein the mechanism is simple, inexpensive in construction, and easy to install.

These and further objects of my invention will appear in the following description when read in connection with the drawings forming a part of this application and in which drawings like reference characters indicate like parts and in which:

Fig. 1 is a diagrammatic illustration of the preferred form of my priming system applied to an internal combustion engine;

Fig. 2 is a diagrammatic illustration of a modified form of the invention in which both fuel 35 and air are supplied to the engine cylinders;

Fig. 3 is a further modification in which the pumps of Figs. 1 and 2 are eliminated and fuel under pressure is admitted to the engine cylinders through an automatic valve;

Fig. 4 is a diagrammatic illustration of still a further modification of my system and in which a liquid fuel is injected and at the same time a gaseous fuel or air is permitted to mix with the liquid fuel;

Fig. 5 is a cross sectional view of the three way ball check valve employed in my system;

Fig. 6 is a sectional view of one form of fuel pump employed in my system;

Fig. 7 is a sectional view through a modified 50 form of fuel pump;

Fig. 8 is a view partially in elevation and partially in cross section of the fuel pump and air valve used with the modification of my system illustrated in Fig. 4;

Fig. 9 is a cross sectional view of the double action hand pump used in the system illustrated in Fig. 1.

Fig. 10 is a cross sectional view of a hand operated priming pump adapted to furnish both liquid fuel and air or gas and this is particularly adapted to the system as shown in Fig. 2 of the drawings;

Fig. 11 is a cross sectional view of an automatic valve used in conjunction with Fig. 3, wherein the pressure generated by a highly volatile explosive gas is utilized to open the valve and permit the passage of gas during the operation of the system.

In Fig. 1 of the drawings the reference character A represents the usual fuel tank and the character B represents an auxiliary fuel tank. Tank B is filled with a liquid fuel having a low boiling point such as butane gas or ether or a mixture of ether and gasoline or a mixture of butane gas and gasoline. Under normal weather conditions, the valve 1 is turned to close communication between pipe 3 and pipe 8 and to permit communication between pipe 4 and pipe 8, thus permitting a charge of priming fuel to be taken from tank A through pipe 1, fitting 5, pipe 4, valve 1 and into pipe 8. On the other hand, when abnormal weather conditions are encountered and it becomes necessary to start the engine at extremely low temperatures the valve 1 is turned to permit communication between pipe 3 and pipe 8 thus permitting a priming charge of highly volatile fuel to be taken from tank B into pipe 8. Pipe 8 is screw threaded to valve D which is more particularly illustrated in Fig. 5. This three way automatic ball check valve permits fuel to enter passage 30, flow past the ball 31, which is spring pressed against its seat by spring 32, and from thence through passage 34 into pipe 10 (Fig. 1), which is screw threaded thereto, through stop cock 2, pipe 11 and into priming pump F.

Priming pump F is more particularly illustrated in Fig. 6 of the drawings and it will be noted that it consists of a cylinder 40 which is attached to the starting motor S by brackets 41. Pipe 11 is attached to the screw threaded removable closure fitting 42 at one end of the cylinder by means of fitting 43. Within the cylinder there is a double cupped, free moving piston 44 which is urged to the rear of the cylinder and against screw threaded removable closure cap 45 by means of a coil spring 46. Tube 47 connects the pressure chamber 48 of starter S with the rear end of cylinder 40 through closure fitting 45.

From the above description, it is obvious that after a working stroke of piston 49 within the starter S, the piston 44 of priming pump F is forced to the rear of cylinder 40 through the pressure of spring 46. As this occurs liquid fuel is drawn from either tank A or B (Fig. 1), depending upon the position of valve 1, through line 8, valve D, pipes 10 and 11 to fill the cylinder of the priming pump F. Under these conditions, the priming system is ready, upon operation of starter S, to deliver a priming charge to the engine.

When motive fluid is admitted to space 48 in starter S (Fig. 6), a portion thereof passes through tube 41 and enters the cylinder 40 of the priming pump behind piston 44, piston 44 then being driven forward to eject the charge of fuel contained therein. The fuel leaves the priming pump through tube 11 (Fig. 1), returns 75 through stop cock 2, tube 10 and enters the three

way automatic ball check valve D at 34 (Fig. 5). Ball 31 is now seated and the fuel which is being forced through the system under high pressure unseats ball 35, which is spring pressed against its seat by spring 36, and leaves the check valve 5 at 37 to enter pipe 9 (Fig. 1). At this point, it may be noted that the tension of springs 32 and 36 may be adjusted by regulating nuts 38 and 39, respectively (Fig. 5).

The fuel coming through pipe 9 (Fig. 1) passes 10 through fitting 24, pipe 21, through distributing fittings 22 and 20, through pipes 19 to atomizing nozzles which project into the various intake manifolds 17.

Because of the high pressure under which the 15 fuel is forced through the system and because of the particular construction of the atomizing nozzles it is possible to entirely eliminate ordinary and conventional carbureting devices 20 usually used in connection with priming systems.

The above describes a complete cycle of operation of my priming system and this operation will be repeated each time the starting motor is operated unless stop cock 2 in Fig. 1 is turned to prevent fuel from entering the priming pump. 25 This stop cock also serves to withhold the injection of the fuel stored in the priming pump when it is desired to operate starter S without injecting a priming charge. It has been found that usually one operation is sufficient to start a 30 heavy airplane engine even in sub-zero weather, but if after the engine has started, it is desired to continue the priming thereof, this can be done through hand pump G (Fig. 1) which draws the supply of fuel from tank A through pipe 6 35 and ejects the fuel through pipe 13 and fitting 24 into pipe 21 where it follows the same course taken by fuel injected into the system by fuel pump F.

This hand pump, which is conveniently located 40 for manual operation, is more particularly illustrated in Fig. 9 of the drawings. By referring to this figure, it will be noted that this pump comprises a casing or cylinder 60 in which there reciprocates a piston 61 having double cups 62 45 in contact with the inner walls of casing 60. This piston is operated through operating handle 63 and operating rod 64. The pump illustrated is a double action pump of which the principles and operation are sufficiently well known to make unnecessary further detailed description, but delivering sufficient pressure and volume to efficiently operate the jet primers.

The modification of my system illustrated in Fig. 2 of the drawings is very much similar to that shown in Fig. 1 and differs therefrom in that fuel pumps F and G are supplemented by air pumps O. In this form of the invention liquid fuel is taken from either tanks A or B through valve 1, pipe 8, three way automatic 60 ball check valve D, pipe 10, stop cock 2 and pipe 11 to enter the fuel pump F. This operation takes place when the spring 46 in fuel pump F which is similar to the pump shown in Fig. 6 returns the piston to the back of the cylinder. 65 When starter S is operated fluid pressure is admitted to both air pump O and fuel pump F through connection 17 and the liquid fuel is expelled from pump F through pipe 11, stop cock 2, pipe 10, ball check valve D, pipe 9, pipe 21 and 70 from there to the fuel inlet of the atomizing nozzles. Air at the same time is expelled from pump O through pipe 12, pipe 16, pipes 18 to the air inlet of the atomizing nozzles.

In a similar manner the hand operated priming 75

5 pump receives its liquid fuel through pipe 6 and discharges the same through pipe 13 and into pipe line 21 thence to the distributing means and the fuel inlet of the atomizing nozzles. Likewise, the hand operated air pump O discharges air through pipe 14, pipe 16, pipes 18 to the air inlet of the atomizing nozzles.

10 The pump of Fig. 10 may be either a single or double acting pump simultaneously operated by a single handle which controls the movement of the liquid piston and air piston of conventional types. More particularly this pump comprises two cylinders 130 and 131 in which reciprocate pistons 132 and 133 respectively. These pistons 15 are attached to a common operating handle 134. Piston 132 in the air cylinder 130 has therein a valve 135 which is spring pressed against its seat on the piston by a flat spring 136. Thus when the handle 134 is drawn toward the operator 20 to draw the pistons to the rear of the cylinder air entering vent 137 passes through valve opening 138 past valve 135 which has been moved from its seat by the force of air pressure against the action of spring 136. During this operation 25 the cylinder outlet 139 is closed by ball check valve 140 which is spring pressed to its seat by coil spring 141, the tension of which spring may be regulated by nut 142. It is now evident that when the operating handle 134 is moved to bring 30 the piston to the forward end of the cylinder, valve 135 will be closed and the air will be trapped in the forward end of the cylinder. After appreciable amount of pressure has been created 35 ball check valve 140 will open and air under pressure will be permitted to flow into pipe 14 of Fig. 2.

40 Since piston 133 is also attached to operating handle 134 its movement is synchronized with the movement of piston 132. Cylinder 131 is the fuel cylinder and is attached at its inlet to pipe 6 of Fig. 2 which in turn communicates with tanks A or B. Fuel enters passage 143 and passes ball check valve 144 to enter cylinder 131 through the restricted passage 145 which is located in the outer end of the casing, when the handle is operated to draw the piston to the rear 45 of the cylinder. The ball check valve 144 is pressed against its seat by coil spring 146 the tension of which may be regulated by nut 147. Upon the opposite movement of the piston liquid 50 fuel within the cylinder is ejected through opening 145 and enters pipe 13 of Fig. 2.

55 Additional features of the pump illustrated in Fig. 10 include a small cone shaped or pointed plunger 148 carried by piston 133 and which is pressed by spring 149 to close opening 145 when the pump is not in operation so as to prevent liquid fuel from leaking through the pump. This fuel pump is packed by packing 150 held in 60 a packing gland by a packing nut 151. Attached to the casing of this pump is a rotatable member 152 which has an aperture therein to engage behind the head of a screw 153. This is provided for the purpose of locking the operating 65 handle against movement when not in operation and it is merely necessary to slightly turn the rotatable member 152 to free the same from screw 153 so as to permit free movement of the operating handle.

70 Since the modified fuel pump shown in Fig. 7 of the drawings may be used equally well with the forms of my invention shown in Figs. 1 and 2, and inasmuch as I prefer it for both types, this pump will now be described. The pump 75 generally indicated at 70 is a differential piston

5 pump in which the pump pressure applied to the liquid fuel is approximately one-fifth the pressure applied to the piston of the fuel pump, that is, the pressure per square inch. It will be noted that cylinder 71 is approximately five times the area of cylinder 72. In these cylinders 10 are mounted for reciprocation pistons 73 and 74 which are in contact with the inner walls of cylinders 71 and 72 respectively. These pistons are normally held at the rear of the cylinders by 15 means of spring 75 and in this position, with stop cock 2 of Figs. 1 and 2 open chamber 71 of the pump will be filled with liquid fuel similarly to that of the pump shown in Fig. 6. 76 is a screw threaded opening adapted to engage the 15 screw threads of the fitting on pipe 47 which leads from starting motor S, and internally screw threaded opening 77 engages the fitting which attaches pipe 11 thereto.

20 It will be noted that when pressure from starter S enters cylinder 72 of this pump piston 74 moving with piston 73 will advance to the front of the cylinder and in so doing will eject the fuel held in cylinder 71. The movement of these pistons may be regulated by adjusting stop screw 78 25 which abuts member 79 carried by the piston structure. In this way the length of the stroke may be regulated. The development of a pump of this type has been found necessary by reason of the fact that some engines require more fuel 30 for priming than others. For instance, a nine cylinder airplane engine requires more fuel for priming than is required by a seven cylinder engine. Therefore, by adjusting screw 78 the length 35 of the stroke of the pump may be increased or diminished as necessary and accordingly the quantity of the priming charge.

40 Another particular object of a pump of this type lies in the fact that the pressure of the liquid fuel will be only about one-fifth that of the pressure per square inch applied to the piston. This reduction in pressure may be desirable for some types of engines in view of the fact that my starter described in the patents above mentioned generates a pressure of approximately 45 2,500 pounds per square inch, which pressure may, for some types of engines be too great when applied directly to the priming system.

50 Another particular advantage gained for the use of a pump of this type is that when pressure is generated and formed in starter S, that it will at the same time enter cylinder 72 of the pump piston 74 and due to the comparative lightness thereof the pressure will operate piston 74 immediately prior to exerting its pressure and consequent operation upon the cylinder of start S to effect the ejection of fuel in fog form at the manifold of each cylinder immediately and instantaneously before the operation of the starter S. This I have found to give the perfect timed 55 relation necessary for successful starting at sub-zero temperatures.

60 In Fig. 3, I have illustrated a slightly modified form of my priming system and in this system, I have provided an auxiliary tank C which 65 may be filled with propane gas or any other highly volatile explosive gas of like characteristics. This gas in the auxiliary tank is in liquid form but due to the fact that propane gas boils at a very low temperature, minus 44° C., a gas pressure of approximately 8½ pounds per square inch at a temperature minus 30° F. is generated within the tank. Pipe line 8 leading from auxiliary tank C, instead of leading to a priming pump as in the other forms of my invention, leads to an 70 75

automatic valve H which is opened by pressure through tube 47 from starter S.

The details of valve H are illustrated in Fig. 11 wherein 108 represents a cylinder to which the pipe line leading from starter S is attached in any approved manner by the union 109 and wherein piston 110, to which is united the valve 111 and valve stem 112 by the screw member 113 extending through the piston 110 into said stem, and where said valve is normally closed by the pressure of the spring member 115 against valve seating 114, which is formed by a cylindrical member 116, screw threadedly attached to the opposite end of the cylinder 108. A flange 119 to hold the usual packing 120 for the valve 110 serves to act as an abutment for the support of spring 115. The cylindrical member 116 embodies pipe attachment 117 for pipe 8 leading to auxiliary tank C and pipe attachment 118 for pipe 21 leading to the distributing means 20 and 22 through tubes 19 to the jets in manifold 17. The pressure from the starter S serves to operate the piston 110 within the cylinder 108 to thereby unseat valve 111, thereby permitting the highly volatile gas under its own pressure to pass from auxiliary tank C through pipe line 8 through the port formed by the unseating of the valve 111 from its seating 114 into the cylinder 116, thence through the pipe attachment 118 to the pipe line 21 and through the distributing means 20 and 22 and tubes 19 to the jets in manifold 17. The operation of this modified system is evident. When pressure is introduced to starter S, a portion thereof passing through tube 47 will open the automatic pressure valve H and permit the explosive gas which is under pressure in tank C to flow through pipe 8, through the automatic valve H, through pipe line 21, through distributing means 20 and 22, through tubes 19 to the jets in manifold 17.

In Fig. 4 of the drawings, I have shown another modified form of an automatic priming system. It will be noted that in addition to gasoline tank A, this system includes the highly volatile liquid fuel tank B and also the auxiliary gaseous fuel tank C shown in Fig. 3. In this form of the invention, I have provided a novel type of priming pump designated at R in Fig. 4 and this priming pump is more particularly illustrated in Fig. 8 of the drawings. This pump is designed to admit both liquid and gaseous fuel to the atomizing jets for automatically forming a liquid and gas mixture in the manifolds and in this pump 47 indicates the tube which connects the pump 40 with the pressure chamber of the starting motor. Forming one end of the pump, is a valve mechanism which communicates with the pump cylinder and which is operated by pressure from said cylinder. 80 represents a liquid fuel inlet to which is screw threaded pipe 8 of Fig. 4 which pipe in turn communicates with gasoline tank A and auxiliary liquid tank B. At 81 of Fig. 8 I have shown a ball which is pressed against the inner end of inlet 8 by means of spring 82, the tension of which may be adjusted by manipulating nut 83. When the piston in priming pump 40 is operated by pressure from the starter, ball valve 81 remains seated and the fuel under pressure moves plunger 85 to the left thus opening passage 86 and permitting liquid fuel to pass from the pump through outlet passage 87 which leads to the atomizing jets through pipe 11 of Fig. 4. It will be noted that plunger 85 is guided in its movement by bearing blocks 88 and 89. Bearing block 89 also serves as the seat for ball 80

which is spring pressed thereagainst by spring 81, the tension of which may be adjusted by manipulating nut 82. Furthermore, the head of plunger 85 is held against the inner face of opening 86 by means of coil spring 88. This valve communicates with auxiliary tank C of Fig. 4 through a pipe from said tank which is threaded to opening 84. This permits gas under pressure to enter the valve and fill chamber 85 where said gas is held from further movement by ball valve 80. Upon operation of the priming pump, as before explained, plunger 85 is moved to the left and ball 80 is unseated to permit the gas trapped in chamber 85 to escape into chamber 86 by passing between plunger 85 and guide block 88. From here the gas leaves the valve through passage 87 to which pipe 12 of Fig. 4 is screw threaded. From this point on, the system illustrated in Fig. 4 is similar in its operation to that illustrated in Fig. 2 of the drawings.

From the above description, it is now clear that I have provided a priming system, with various modifications, which will operate in timed relation with the engine starting device and which at the same time operates to atomize the fuel sufficiently well to provide effective priming under even the most adverse conditions. It will be further noted that my priming fuel is atomized to a fine state without the use of the usual fuel carburetors.

Due to the fact that pressure ranging up to 2500 pounds per square inch is used in the operation of the starter S, the pressure in the fuel priming system is necessarily very high and this in turn used through the jets in the manifold 17, which jets are constructed for use under high pressure, will atomize fuel to a very fine swirling spray which, by virtue of the shape of my atomizing jets, will be injected into the manifold or cylinders of the engine in the form of a broad cone shaped mist or fog. Due to the fact that the engine is being turned over at a high speed the atomized fuel will be drawn into the cylinders in a suspended condition so that these suspended particles of liquid fuel will have a great deal of surface exposed to the air in the cylinder which surface will absorb the heat of compression so that the whole is immediately and completely gasified to form a perfect explosive mixture. Tests have demonstrated that this system will operate satisfactorily regardless of extreme low temperatures of the engine or extreme low temperatures of the liquid fuel used.

In priming particular types of engines I have found it advantageous to direct the spray or fog from the nozzle in a direction substantially opposite to the flow of air being sucked or about to be sucked in to the manifold by the operation of the cylinders of the engine. On such occasions I prefer to use a nozzle having a face thereof disposed at an angle ordinarily greater than 15° to 30° as heretofore specified and at such angle as is proper to direct the fuel to the center line of air flow in the intake manifold dependent, as will be obvious, upon the circumferential area of the conduit. The pressure of the fog or spray is of course less than the pressure of the inrushing air.

It is to be clearly understood that my system and the various parts thereof may be modified and that the foregoing description and the accompanying drawings are merely for the purpose of illustration and are not to be construed as limiting the invention, but my invention may be used in other ways without departing from the spirit as defined by the following claims.

What I claim is:

1. In a priming system for internal combustion engines, a starting device for said engine adapted to generate fluid pressures for operating said starting device, a priming device in the fuel line between the starting device and the engine for delivering fuel to the engine intake, and means for operating the fuel priming device for delivery of priming fuel to the engine under the same pressures generated by and in timed relation to the operation of said starting device. 5
2. In combination with an internal combustion engine, a starting device for said engine adapted to generate gas pressures for operating said starting device, a priming device in the fuel line for said engine and located between the starting device and the intake of said engine, and means for diverting a part of said gases generated by said starting device for operating the priming device. 10
3. In combination with an internal combustion engine, a starting device for said engine adapted to generate gas pressures ranging up to 2500 pounds per square inch for operating said starting device, a fuel priming device for said engine located in the fuel line between the starting device and the engine intake, and means for operating the priming device for delivery of fuel to the engine under the same pressures generated by and in timed relation to the operation of said starting device. 15
4. In combination with an internal combustion engine, a starting device therefor adapted to generate gas pressures for operating the starting device, a fuel priming system associated with said starting device and including a supply of highly volatile fuel adapted under pressure generated by the volatilization of said fuel at minus zero Fahrenheit temperatures to be delivered to the internal combustion engine, a valve intermediate said fuel supply and the intake of said engine, and means for automatically operating said valve for delivery of fuel to said engine through the pressures generated by and at the time said starting device is operated. 20
5. In combination with an internal combustion engine, a starting device for said engine adapted to generate fluid pressures for operating said starting device, a priming device for delivering fuel to the engine intake, a pump for delivering air to said engine intake, and means for operating the fuel priming device and the air pump for delivery of priming fuel and air to the engine under the same pressures generated by and in timed relation to the operation of said starting device. 25
6. In combination with an internal combustion engine, a starting device for said engine adapted to generate fluid pressures for operating said starting device, a pump for delivering priming fuel to the engine, a tank for containing highly volatile fuel for delivery to said engine under pressure generated by the volatilization of said fuel within said tank at minus zero Fahrenheit temperatures, a valve intermediate the highly volatile fuel tank and the intake of the engine, and means for operating the fuel pump and said valve under the pressures generated by and in timed relation to the operation of said starting device for delivery of both priming fuels to the engine. 30
7. In combination with an internal combustion engine, a starting device for said engine adapted to generate fluid pressures for operating said starting device, a fuel tank, a fuel pump, a pipe line connecting said fuel tank with the fuel pump, an automatic valve in said pipe line, means to normally maintain a supply of fuel in the fuel pump and the pipe line between said pump and the automatic valve when the pump is in its inactive relation, a pipe line extending from said automatic valve to the intake of the internal combustion engine, and means for operating said fuel pump and said automatic valve by the pressures generated by the starting device and at the time said starting device is operated and for delivery of priming fuel to the intake of said engine. 35
8. In a priming system for internal combustion engines, means for generating fluid pressures for operating said priming system at the time the system is operated, said priming system including a pump located in the fuel line between the pressure generating means and the engine intake, means for delivering said fluid pressure to the priming pump for operating the same and priming the engine, and means to create a predetermined pressure change in said priming system for altering the overall pressure of the system. 40
9. In a priming system for internal combustion engines, means for generating fluid pressures for operating said priming system at the time the system is operated, said priming system including a pump located in the fuel line between the pressure generating means and the engine intake, means for delivering said fluid pressures to the priming pump for operating the same and priming the engine, and adjustable means to alter the output of the priming system. 45
10. In combination with an internal combustion engine, a starting device for said engine adapted to generate gas pressures for operating said starting device, a priming system for said engine including a fuel pump located in the fuel line between the starting device and the engine intake, means for diverting a part of said gases generated by said starting device for operating the fuel pump, and means to create a predetermined pressure change in said priming system, thereby altering the overall pressure of said system. 50
11. In combination with an internal combustion engine, a starting device for said engine adapted to generate fluid pressures for operating said starting device, a priming device for said engine located in the fuel line between the starting device and the engine intake, means for diverting a part of said gases generated by said starting device for operating the priming device, and means for adjusting the operating mechanism of said priming device to control the amount of fluid supplied to the engine. 55
12. In combination with an internal combustion engine, a starting device for said engine adapted to generate fluid pressures for operating said starting device, a priming device for said engine located in the fuel line between the starting device and the engine intake and adapted to operate with a maximum output, means for diverting a part of the gases generated by said starting device for operating said priming system, and adjustable means to alter the output of the priming device. 60

ROSCOE ALEXANDER COFFMAN. 70
